DESCRIPTION

U.S. PATENT DOCUMENTS

FIG. 1 is a top perspective view of the new design for an electrical box and conduit support plate in accordance with the present invention;

D449,218 S 10/2001 Vrame
D462,939 S 9/2002 Dinh
7,078,618 B2 * 7/2006 Dinh H02G 3/123
174/481

FIG. 2 is a first side elevation view of the electrical box and conduit support plate shown in FIG. 1;

D531,010 S 10/2006 Vrame
7,300,025 B2 11/2007 Korcz
7,439,443 B2 10/2008 Dinh
7,472,875 B2 6/2009 Rinderer

FIG. 3 is a second side elevation view of the electrical box and conduit support plate shown in FIG. 1;

FIG. 4 is a top plan view of the electrical box and conduit support plate shown in FIG. 1; and,

FIG. 5 is a bottom plan view of the electrical box and conduit support plate shown in FIG. 1.

The broken lines shown represent portions of the electrical box and support plate that form no part of the claimed design.
